Primary Examiner — Michael A. Pratt(74) *Attorney, Agent, or Firm* — Samuel M. Korte; Max M. Ali(57) **CLAIM**

The ornamental design for a sighting device mount, as shown and described.

DESCRIPTION

FIG. 1 is a rear perspective view of a sighting device mount according to the present invention;

FIG. 2 is a front perspective view of the sighting device mount;

FIG. 3 is a top view of the sighting device mount;

FIG. 4 is a bottom view of the sighting device mount;

FIG. 5 is a rear view of the sighting device mount;

FIG. 6 is a front view of the sighting device mount;

FIG. 7 is a left side view of the sighting device mount;

FIG. 8 is a right side view of the sighting device mount; and,

FIG. 9 is an environmental perspective view of the sighting device mount.

The structural features depicted by broken lines have been shown for the purpose of illustrating portions of the marine mount that form no part of the claimed design.
